Primary Examiner — John A Voytek

(74) Attorney, Agent, or Firm — Pandiscio & Pandiscio

(57) **CLAIM**

The ornamental design for a filter, as shown and described.

DESCRIPTION

FIG. 1 is a top perspective view of the filter;
 FIG. 2 is a top view of the filter, taken from the frame of reference of FIG. 1;
 FIG. 3 is a bottom view of the filter, taken from the frame of reference of FIG. 1;
 FIG. 4 is a side view, in elevation, of the left side of the filter, taken from the frame of reference of FIG. 1;
 FIG. 5 is a side view, in elevation, of the right side of the filter, taken from the frame of reference of FIG. 1;
 FIG. 6 is a front view of the filter, taken from the frame of reference of FIG. 1;
 FIG. 7 is a rear view of the filter, taken from the frame of reference of FIG. 1; and,
 FIG. 8 is a bottom perspective view of the filter.
 The broken lines are included for the purpose of illustrating unclaimed portions of the filter and form no part of the claimed design.

1 Claim, 8 Drawing Sheets(56)
